DESIGN FOR A LIGHTING FIXTURE

Herman N. Gordon, New York, N. Y., assignor to Isidor Rosenblatt and Max Rosenblatt, copartners doing business as Globe Lighting Fix-ture Mfg. Co., Brooklyn, N. Y.

Application June 6, 1941, Serial No. 101,323

Term of patent 3½ years

To all whom it may concern:

Be it known that I, Herman N. Gordon, a citizen of the United States, residing in New York, county of Bronx, and State of New York, have invented a new, original, and ornamental Design for a Lighting Fixture, of which the following is a specification, reference being had to the accompanying drawing, forming a part thereof.

Fig. 1 is a perspective view of a lighting fixture showing my new design.

Fig. 2 is an end view thereof.

The side and end not shown are substantial duplicates of those illustrated.

I claim:

The ornamental design for a lighting fixture, as shown and described.

HERMAN N. GORDON.
